UNITED STATES PATENT OFFICE.

CHARLES D. SPATES, OF DIGBY, NOVA SCOTIA, CANADA, ASSIGNOR OF ONE-HALF TO CLARENCE JAMESON, OF DIGBY, NOVA SCOTIA, CANADA.

WINDOW LIFT-LOCK AND HOLDER.

987,759.

Specification of Letters Patent. Patented Mar. 28, 1911.

Application filed July 23, 1910. Serial No. 574,293.

To all whom it may concern:

Be it known that I, CHARLES D. SPATES, a subject of the King of Great Britain, residing at Digby, in the Province of Nova Scotia and Dominion of Canada, have invented a new and useful Window Lift-Lock and Holder, of which the following is a specification.

The invention relates to a lift lock and holder for window sashes.

The object of the present invention is to improve the construction of sash locks, and to provide a simple, inexpensive and efficient device, adapted to be readily applied to windows having balance sashes, and adapted to enable the same to be readily raised and lowered, and capable of holding the sash at any adjustment and of securely locking a sash in its closed position.

With these and other objects in view, the invention consists in the construction and novel combination of parts hereinafter fully described, illustrated in the accompanying drawing, and pointed out in the claims hereinafter appended; it being understood that various changes in the form, proportion, size and minor details of construction, within the scope of the claims, may be resorted to without departing from the spirit or sacrificing any of the advantages of the invention.

In the drawing: Figure 1 is an elevation, partly in section, of a window equipped with lock lifts and holders, constructed in accordance with this invention. Fig. 2 is an enlarged vertical sectional view of the lock lift and holder. Fig. 3 is a horizontal sectional view of the same. Fig. 4 is a detail perspective view of the bolt actuating lever. Fig. 5 is a similar view of the sliding bolt.

Like numerals of reference designate corresponding parts in all the figures of the drawing.

In the embodiment of the invention illustrated in the accompanying drawing, the lock lift and holder comprises in its construction a sliding bolt 1, guided in a casing 2 and actuated by a lever 3 to move the bolt into its engaging position. The lever is connected with a sash balancing and lifting spring 4, but an elastic cord may be substituted for the spring, and the lever may also be connected with an ordinary weighted cord, or other form of sash balance. The casing 2, which is mortised in the side of the sash 5, is composed of spaced vertical sides

and an inner integral vertical connecting wall 6. The bottom of the casing is preferably formed by a block or piece 7, riveted or otherwise secured between the sides of the casing and spacing the sides and forming a support for the sliding bolt 1.

The sliding bolt 1, which is arranged horizontally, is composed of a rectangular body portion and a rounded stem 8, extending through the wall 6 of the casing and through the side bar or member of the frame of the sash, and equipped at its outer end with a ring 9, or other suitable means for enabling it to be readily grasped by the operator. The rectangular body portion of the bolt rests upon the block or piece 7, and is provided in its upper edge with a straight longitudinal recess 10, receiving a guiding pin or rivet 11, which pierces the sides of the casing. The bolt slides upon the bottom of the casing and is guided by the same and by the pin 11, which also limits the sliding movement of the bolt and prevents the same from becoming disengaged from the lever.

The lever 3, which is arranged in an upright position, is curved longitudinally to form angularly related arms, and is pivoted at an intermediate point between the sides of the casing by means of a pin or rivet 12. The lever is tapered longitudinally, and its lower terminal 13 is rounded and is fitted in an inclined bearing recess 14, formed in the upper edge of the body portion of the bolt in rear of the guiding recess 10. The upper end 15 of the lever is bifurcated and is equipped with a pin 16, extending across the slot or bifurcation of the upper end of the lever and engaged by a hook 17, which has its shank 18 secured within the slotted end of the coiled spring 4. The spring, when placed under tension, tends to draw the upper end of the lever upwardly and to move the engaging end of the bolt inwardly into engagement with the side of the window frame 19, which is equipped at the bottom with a keeper 20, consisting of a metallic plate provided with a recess conforming to the configuration of the end of the bolt and enabling the same to securely lock the sash in its closed position. When the bolt is withdrawn by hand from engagement with the window frame, the spring 4 will operate to lift the sash, and when the bolt is released the spring will carry the same into engagement with the window frame.

The frictional engagement of the bolt with the window frame is sufficient to hold the sash in any adjustment.

The upper end of the spring 4 is attached 5 to the window frame by a screw eye 21, or other suitable means and each side of the sash may be equipped with a lock lift and holder, or only one lock lift may be employed and in such event an anti-friction 10 roller should be mounted on the upper portion of the side of the sash not supplied with the sash lock.

Having thus fully described my invention, what I claim as new and desire to secure by 15 Letters Patent, is:—

1. In a device of the class described, the combination with a sash balance, of a casing designed to be mounted on a sash, a horizontal slideable bolt guided in the casing and extending through the side of the sash and provided with operating means, said bolt being also provided in its upper edge at a point intermediate of its ends with a bearing recess, and an upright lever 25 concealed within the casing and located above the bolt and fulcrumed at an intermediate point and having angularly related upper and lower arms, the upper arm being connected with the sash balance and the 30 lower arm being fitted in the recess, whereby the sash balance will actuate the bolt and move the same to its engaging position.

2. A device of the class described comprising a sash balancing spring provided at its 35 lower end with a hook, a horizontally slideable bolt located below the spring and provided in its upper edge with a bearing recess and having operating means at its outer

end adapted to extend through the side of the frame of a sash, and an upright lever 40 located above the bolt and pivoted at an intermediate point and having angularly related upper and lower arms, the lower arm being fitted in the recess of the bolt and the upper arm being bifurcated to receive 45 the hook of the spring and having means for engaging the same.

3. A device of the class described including a casing having a horizontal bottom guiding portion and designed to be mortised 50 in the sash, a horizontal bolt consisting of a rectangular body portion slideable on the bottom of the casing and provided with an operating stem extending through the same and adapted to project exteriorly of a sash, 55 said bolt being also provided in the upper edge of its body portion with a bearing recess and having a stem guiding recess in advance of the same, a pin mounted in the casing and extending through the guiding 60 recess, and a curved lever concealed within the casing and pivoted at an intermediate point above the bolt and having its lower end fitting in the bearing recess of the said bolt and engaging the same, said lever being 65 provided at its upper end with means for connecting it to a sash balance, whereby the latter is adapted to move the bolt to its engaging position.

In testimony, that I claim the foregoing 70 as my own, I have hereto affixed my signature in the presence of two witnesses.

CHARLES D. SPATES.
